COOLER

Charles I. Brown, Duboistown, Pa.

Application April 29, 1938, Serial No. 205,078

1 Claim. (Cl. 62—101)

This invention relates to coolers especially adapted for chilling the contents of containers and has for the primary object the provision of a device of this character which will circulate 5 in direct contact with containers a chilled liquid to quickly lower the temperature of the contents of said containers and may maintain the temperature of the contents at substantially the same temperature as the chilling liquid and will 10 provide a device which will be economical in operation and may have a portion thereof in use for chilling containers by the chilled liquid while another portion thereof may be employed for dry cooling or rendered entirely inoperative and 15 thereby reduce operating costs of the device in entirety.

With these and other objects in view, this invention consists in certain novel features of construction, combination and arrangement of parts 20 to be hereinafter more fully described and claimed.

For a complete understanding of my invention, reference is to be had to the following description and accompanying drawings, in which

25 Figure 1 is a top plan view illustrating a cooler constructed in accordance with my invention with a fragmentary portion of the cover thereof shown in an open position.

Figure 2 is a vertical sectional view taken on 30 line 2—2 of Figure 1.

Figure 3 is a transverse sectional view taken on line 3—3 of Figure 2.

Figure 4 is a transverse sectional view taken on line 4—4 of Figure 2.

35 Figure 5 is a transverse sectional view taken on line 5—5 of Figure 2.

Figure 6 is a fragmentary transverse sectional view illustrating a modified form of my invention.

40 Referring in detail to the drawings, the numeral 1 indicates a trough-like cabinet, open at its upper end and equipped with a hinged cover 2 for the purpose of closing and opening said cabinet. The cover and the walls of the cabinet

45 are of the insulated type and arranged in the cabinet is a transverse partition 3 also of an insulated construction and has therein a doorway 4 controlled by a hinged door 5. A partition 3 divides the cabinet 1 into chilling chambers 6 and

50 7 and the doorway 4 provides communication between said chambers when the cover is in a closed position. Communication between said chambers 6 and 7 may be interrupted by closing the door 5. Supported one above the other in the

55 chamber 7 by the partition 3 are perforated pipes

8 having communication with the chamber 6. The purpose of the perforated pipes is to transfer chilled liquid from the chamber 6 to the chamber 7 in spray form and are provided with cutoff valves 9.

A chilling unit 10 is arranged in the chamber 6 of the cabinet at one end of said chamber and forms a part of a conventional type of mechanical refrigerating system and as the latter forms no part of the present invention it is not shown.

10 It is to be understood that the mechanical refrigerating system is located exteriorly of the cabinet. A baffle plate 11 extends transversely of the cabinet within the chamber 6 adjacent the chilling unit 10 and is spaced a limited dis-

15 tance from the bottom of the cabinet to permit liquid to flow thereunder. Arranged exteriorly of the cabinet is a liquid circulating pump 12 of any well known construction, the inlet pipe

13 thereof extending into the cabinet through 20 the chamber 6 adjacent the bottom of the cabinet and into the chamber 7. The outlet pipe

14 of the pump extends into the cabinet and terminates over the chilling unit in the form of 25 a nozzle 15 so as to spray liquid on a chilling unit for gravitation thereover when the pump 12 is in operation, it being understood that the pump takes the liquid from the chambers 6 and 7.

The inlet pipe 13 has a cut-off valve 16 located in the chamber 7 for closing the portion 30 of the inlet pipe lying in the chamber 7 to the pump. A stand pipe 17 is connected with the inlet pipe and is located vertically within the chamber 6 and has a cutoff valve 18.

The cut-off valve 18 when opened will permit the pump 35 to obtain liquid from the chamber 6 still maintaining the liquid in said chamber at a predetermined level, it being understood that the liquid gravitating over the chilling unit flows into the chamber 6 from under the baffle 11. A sup-

ply pipe 19 having a cutoff valve 20 is connected to the inlet pipe 13. The purpose of the supply pipe 19 is to furnish liquid to the chambers 6 and 7 when necessary.

In operation, containers to be chilled are 45 grouped in the chambers 6 and 7 and with the pump 12 in circulation the chilling liquid is circulated over the chilling unit into the chamber 6 coming in a direct contact with the containers

7. The chilled liquid passes from the chamber 6 into the chamber 7 by either of the pipes 8 depending on which pipe is open to the chamber 6. The chilled liquid sprays from the pipe

50 8 onto the container in the chamber 7. The liquid is taken from the chambers 6 and 7 by 55

the pump 12 through the inlet pipe 13. With this arrangement the containers may be chilled by having the chilling liquid circulating in direct contact therewith or by having chilled liquid sprayed against the containers. Sometimes it may be desirable to only use the chamber 6 for chilling containers and the chamber 7 may be cutoff therefrom by closing the valves 9 and 16 for rendering the chamber 7 inoperative, consequently reducing the cost of operation. Then again it may be desired to keep articles cool in the chamber 7 while the chamber 6 is in use for chilling containers by having the chilling liquid coming in direct contact with the containers. The door 5 under these conditions is moved into an open position to permit circulation of air between the chambers 6 and 7.

A baffle 20 may be employed in lieu of the baffle 11. The baffle 20 extends to the bottom of the cabinet and its lower portion has a plurality of ports 21 to permit the chilling liquid to

flow through the lower portion of the baffle from the chilling unit to the chamber 6.

The pipes 8 include angularly related portions so that chilling liquid may be sprayed onto the containers in the chamber 7 from various angles. 5

What is claimed is:

A chilling device comprising a cabinet, a partition dividing said cabinet into separable chambers adapted to contain liquid and having a doorway, a door for opening and closing said doorway of the partition, valve controlled perforated pipes having their inlets communicating with one of said chambers and extending into the other chamber and supported by the partition, a chilling means located in said one of the chambers, 15 and a circulating means for receiving liquid from said chambers and discharging said liquid onto the chilling means for return to said one of the chambers and to the other chamber by way of said perforated pipes. 10

CHARLES I. BROWN. 20
